UNITED STATES PATENT OFFICE.

CHARLES A. CORRELL, OF VINTON, IOWA.

DESIGN FOR A DISPLAY-RACK.

44,400.

Specification for Design.

Patented July 29, 1913.

Application filed March 17, 1913. Serial No. 755,035. Term of patent 14 years.

To all whom it may concern:

Be it known that I, CHARLES A. CORRELL, a citizen of the United States of America, residing at Vinton, in the county of Benton and State of Iowa, have invented a new, original, and ornamental Design for Display-Racks, of which the following is a specification, reference being had to the accompanying drawing, forming part thereof.

In the drawing, Figure 1 is a perspective

view of a display rack showing my new design; Fig. 2 is a side elevation of the same.

I claim—

The ornamental design for a display rack, as shown.

CHARLES A. CORRELL.

Witnesses:

P. J. CARTER,

L. J. KIRKLAND.
